UNITED STATES PATENT OFFICE

ANTON LAUTERER, OF BERLIN-SCHONEBERG, GERMANY, ASSIGNOR TO C. LORENZ
AKTIENGESELLSCHAFT, OF BERLIN-TEMPELHOF, GERMANY

TRANSMITTER

Application filed July 24, 1928, Serial No. 295,084, and in Germany January 21, 1928.

The present invention refers to an undamped transmitter, the diaphragm of which is provided with a nipple. The electrode of the undamped transmitter is equipped with a ring projecting into the carbon-powder. Hereby the burning of the carbon-powder is avoided, which burning may happen when—at the moment of taking up the receiver—ringing-current impulses pass the microphone. When—at such a moment—a gap is formed between the diaphragm and the carbon-powder, or the electrode and the carbon-powder, the current may take its way through particles of carbon adhering to the diaphragm and its felt-ring or at the electrode. By those momentarily strong impulses these particles become red hot and are destroyed. In order to do away with this drawback transmitters have already been created the diaphragms of which are equipped with nipples and the electrodes with rings projecting into the carbon-powder.

These well known transmitters, however, are subject to certain inconveniences. It may happen, that single particles at the diaphragm and at the electrode of the transmitter may begin to burn and destroy the felt-ring enveloping the powder. Besides, by this felt-ring enveloping the powder the microphone itself is damped, and such microphones are not very efficient.

The present invention, now, has for its object a transmitter which avoids these detrimental inconveniences of the transmitters known. This is reached by enclosing the carbon grains or powder in a capsule covered by a plate, through which latter the nipple of the diaphragm projects into the mass of the carbon-powder.

The drawing annexed is a practical example of the invention partly in section and partly in elevation. The diaphragm 1 has a conical-ended nipple 2. It is clamped into a casing 7 covered on its top by a disk 8 in the usual way. The capsule or chamber 4 containing the carbon-powder 3 is fixed on a disk 5 made of insulating material. The electrode 6 which is mounted within the capsule 4 is provided with a ring or annular projection 6'. This latter may be fixed to the

electrode or the entire electrode including the ring may be made of one piece of material. The most advantageous constellation is when the layer of carbon-powder between the cone surface of the nipple 2 and the ring of the electrode 6 is equally thick at all points. This is the case when the mantle-line of the nipple 2 is in parallel with the oblique face of the ring of the electrode 6. In that case the layer of carbon-powder between these two surfaces offers an equal resistance at every point and current passes everywhere, and not merely at the top of the nipple.

The felt-ring 10 is arranged between the cover-plate 9 of capsule 4 and the diaphragm 1. This felt-ring is very small in size and the microphone is not damped by it. The cover-plate 9 of capsule 4 is provided with a hole of sufficient size as to allow a free oscillation of the nipple 2.

Capsule 4 may effectively be lined with a hard insulating substance. This substance may, for instance, be mica. It is preferred to use a hard insulating substance in order to prevent deleterious consequences in case single carbon-particles should unavoidably be burned in consequence of the presence of strong currents.

What I claim is:

1. An undamped transmitter employing carbon powder and having means for preventing burning of the carbon granules, comprising a diaphragm, a capsule enclosing the body of carbon-powder, an electrode in said capsule, a plate closing the side of said capsule facing the diaphragm and having an opening therein, a nipple on the diaphragm extending loosely into the capsule and body of carbon-powder therein through the opening in said plate, and means for closing the joint between the nipple and wall of the opening against the escape of the carbon granules.

2. An undamped transmitter employing carbon powder and having means for preventing burning of the carbon granules comprising a diaphragm, a capsule enclosing the body of carbon-powder, an electrode in said capsule, a plate closing the side of said cap-

sule facing the diaphragm and having an opening therein, a nipple on the diaphragm having a portion of uniform diameter projecting through the opening in the plate and terminating in a conical portion loosely extending into the body of carbon-powder, and a felt-ring enclosing the portion of the nipple of uniform diameter between said plate and said diaphragm and closing the joint between the nipple and wall of the opening in the plate against the escape of carbon particles.

3. An undamped transmitter employing carbon granules and having means for preventing burning of the carbon granules comprising a diaphragm, a capsule enclosing the body of carbon-powder, an electrode in said capsule and provided with a conducting ring projecting into the body of carbon powder, a plate covering the side of the capsule facing the diaphragm and having an opening therein, a nipple on the diaphragm extending loosely through said opening and into the carbon-powder in the capsule and a felt-ring enclosing the nipple between said plate and said diaphragm and closing the joint between the nipple and wall of said opening in the plate.

In testimony whereof I have affixed my
signature.

ANTON LAUTERER.
